UNITED STATES PATENT OFFICE.

ERNEST E. BROSS, OF DETROIT, MICHIGAN, ASSIGNOR TO THE TRAUB MANUFACTURING COMPANY, OF DETROIT, MICHIGAN, A CORPORATION OF MICHIGAN.

DESIGN FOR A FINGER RING.

Application filed December 6, 1922. Serial No. 4,505. Term of patent 14 years.

To all whom it may concern:

Be it known that I, ERNEST E. BROSS, a citizen of the United States, and a resident of Detroit, in the county of Wayne and State of Michigan, have invented a new, original, and ornamental Design for Finger Rings, of which the following is a specification, reference being had to the accompanying drawing, forming part thereof.

In the drawing, Figure 1 is a side elevation on a large scale of a finger ring embodying my new design. Figure 2 is an edge view thereof on the same scale.

I claim:—

The ornamental design for a finger ring, as shown.

ERNEST E. BROSS.
